UNITED STATES PATENT OFFICE.

SETH A. RHODES, OF CHICAGO, ILLINOIS.

EXPLOSIVE-ENGINE.

1,086,857.

Specification of Letters Patent. Patented Feb. 10, 1914.

Application filed December 1, 1910. Serial No. 595,088.

To all whom it may concern:

Be it known that I, SETH A. RHODES, a citizen of the United States, and a resident of Chicago, county of Cook, and State of Illinois, have invented certain new and useful Improvements in Explosive-Engines, of which the following is a full, clear, and exact description.

The improvement relates to explosive engines and more particularly to the valve mechanism therefor.

The invention seeks to provide a simple and effective valve mechanism which can be economically manufactured and readily maintained in good working condition and which eliminates the necessity of employing cam actuated, spring-held puppet valves.

The invention consists in the features of improvement hereinafter set forth, illustrated in the preferred form in the accompanying drawings and more particularly pointed out in the appended claims.

Figure 1 is a view in elevation of an explosive engine with the improved valve mechanism applied thereto. Figs. 2, 3 and 4 are partial views similar to Fig. 1 with the parts shown in different positions.

The invention is particularly adapted and is shown as applied to a four-cycle internal combustion engine. The engine cylinder 1 is upright and is mounted upon a suitable crank case 2. The engine piston 3 is connected, as usual, by a pitman rod 4 to a crank 5 on the engine shaft 6, the shaft being journaled in the usual manner in suitable bearings formed upon the crank case 2. The engine cylinder shown is provided with a water jacket 7 and with an igniter plug 8.

The admission and exhaust of the gases to and from the engine cylinder is controlled by two slide valves, one of which is positively reciprocated by a pitman driven from the engine shaft. This latter valve has a lost motion connection with the other slide valve and is arranged to intermittently reciprocate the same. The second slide valve is frictionally held in position and has periods of rest at the opposite ends of its movement. The slide valves are preferably arranged in a valve casing 9 which is cast in one piece with the engine cylinder and is arranged at one side thereof with its longitudinal axis parallel with the longitudinal axis of the engine cylinder. The water jacket 7, as shown, surrounds the upper ends

of the engine cylinder 1 and valve casing 9. The valve casing is provided at its lower end and in its outer side wall with an inlet port 10 for the explosive mixture, and the upper end of the cylindrical bore of the valve casing forms an exhaust port 11. The inlet port 10 communicates with a suitable carburetor or the like and the exhaust port 11 communicates with a suitable muffler, or is open to the atmosphere. Between the inlet and exhaust ports and, in the form shown, adjacent its upper end, the valve casing is provided with a port 12 which communicates with the upper or head end of the engine cylinder 1. The main slide valve preferably comprises a piston 13 which fits within the cylindrical bore of the valve casing 9 and is reciprocated or moved back and forth over the cylinder port 12 to alternately connect the same to the inlet and exhaust ports 10 and 11. In the preferred form shown, the piston valve 13 is mounted upon the upper reduced end of a piston rod 14 and is removably held in position thereon by a nut 15. The lower end of the piston rod 14 is connected to a piston-like cross head 16 which is fitted within the lower end of the cylindrical bore of the valve casing 9 and is connected to the upper end of a pitman rod 17. The lower end of the pitman rod 17 engages a suitable crank or eccentric on a valve shaft 18. In the form shown, the valve shaft 18 is journaled within the crank casting 2 and is provided with a crank 19 to which the lower end of the pitman 17 is suitably coupled. Two-to-one gears 20 and 21 mounted upon the engine shaft 6 and valve shaft 18 serve to rotate the latter shaft at half the speed of the engine shaft.

The piston cross head 16 is provided with an upwardly extended sleeve portion 22 which fits the bore of the valve casing 9 and which is provided on one side with an elongated port 23 that always communicates with the explosive mixture inlet 10. The supplemental slide valve is preferably in the form of an open ended cylindrical sleeve 24 which fits within the bore of the valve casing 9 and is arranged between the piston valve 13 and the sleeve-like portion 22 of the cross head. The opposite ends of the valve sleeve 24 are alternately engaged by the reciprocating piston valve 13 and sleeve 22, so that the valve sleeve is intermittently reciprocated and is moved back and forth over the port 110

12. The space between the lower face of the piston valve 13 and the upper edge of the sleeve 22 is greater than the length of the valve sleeve 24, so that the latter has a lost motion connection with the main piston valve 13 and in view of this lost motion connection, the valve sleeve has periods of rest at the opposite ends of its movement. The valve sleeve 24 is frictionally held in position within the valve casing and is preferably provided, as shown, with a packing ring 25 set within a groove therein.

In the drawings, the connecting gears between the engine and valve shafts are set 15 to effect the operation of the engine shaft in right hand direction as indicated by the arrows shown in the drawings. As shown, the crank or eccentric of the valve shaft has considerable angular advance or lead 20 over the crank of the engine shaft. In Fig. 1 the parts are shown in the position assumed just as the engine piston 3 is about to commence its working stroke. At this time the cylinder port 12 is closed by the 25 sleeve valve 24. During the working stroke of the piston, the parts move from the position shown in Fig. 1 to that shown in Fig. 2. That is to say, during the working stroke of the engine piston 3 the piston- 30 valve 13 is in engagement with the upper edge of the sleeve valve 24 and both valves are moved downwardly, or toward the inlet port 10, until, at the end of the working stroke, the piston valve 13 moves past the 35 cylinder port 12 and places the cylinder port in communication with the exhaust port 11 of the valve casing.

During the exhaust stroke of the engine piston 3, the parts move from the position 40 shown in Fig. 2 to that shown in Fig. 3, and the exhaust gases are forced by the engine piston 3 out through the cylinder port 12 and through the exhaust port 11. At the end of the exhaust stroke of the engine piston 45 ton, the port 12 is closed by the piston valve 13. By reason of the lost motion connection between the sleeve valve 24 and the piston valve, the sleeve valve has a period of rest at its lowermost position shown in Fig. 2, 50 until it is engaged by the sleeve 22 of the piston cross head 16. By reason of this arrangement, the upward movement of the piston valve from the position shown in Fig. 3 places the cylinder port 12 in communication with the inlet port 10 and the 55 explosive mixture is drawn into the cylinder through the valve casing and port 12 during the suction stroke of the engine piston 3. During the suction stroke the parts 60 move from the positions shown in Fig. 3 to those shown in Fig. 4 and, as shown, at the end of the suction stroke, the sleeve valve is shifted to its uppermost position to close the port 12. By reason of the lost motion 65 connection, the sleeve valve 24 has a period

of rest in its uppermost position during the compression stroke of the engine piston or as the parts move from the positions shown in Fig. 4 back to those shown in Fig. 1. At the end of the compression stroke, the lost motion between the main piston valve and supplemental sleeve valve is taken up and the parts are ready for the next cycle of operations. During the periods of rest of the sleeve valve 24, it is frictionally held in position by the engagement of its walls and of its packing ring 25 with the walls of the cylindrical valve casing.

In accordance with the preferred plan of the invention, the main and supplemental slide valves are of cylindrical form, as indicated, since with this form the valves cannot be unseated by pressure exerted thereon through the cylinder port 12, and since this form provides very large bearing surfaces for the valves which cannot readily be worn. It is obvious that the valve mechanism is extremely simple in construction, both valves positively operate and the necessity of employing cam operated, spring-held, puppet valves, which readily wear and get out of order, is avoided. The piston valve 13 is readily accessible and can be easily removed through the exhaust port 11 and when this is done, the sleeve valve 24 can be easily removed. Both valves can therefore be readily repaired or renewed. The valve mechanism has been found to be extremely quiet and efficient in operation. By changing the angular advance or lead of the crank or eccentric on the valve shaft 18 the engine shaft can be operated in the reverse, left-hand direction.

It is obvious that numerous changes can be made in the details set forth without departure from the essentials of the invention as defined in the claims.

I claim as my invention:

1. In an explosive engine, the combination with the engine cylinder, piston and crank shaft, of main and supplemental slide valves for controlling the admission and exhaust of gases to and from the engine cylinder, means driven by the crank shaft for reciprocating said main valve, the latter having a lost-motion connection with said supplemental valve, arranged to engage and shift the same at the opposite ends of the movement of said main valve, substantially as described.

2. In an explosive engine, the combination with the engine cylinder, piston and crank shaft, of main and supplemental slide valves for controlling the admission and exhaust of gases to and from the engine cylinder, means driven by the crank shaft for reciprocating said main valve, the latter having a lost-motion connection with said supplemental valve, arranged to engage and shift the same at the opposite ends of the

movement of said main valve, said supplemental valve being frictionally held in position and having periods of rest at the opposite ends of its movement, substantially as described.

3. In an explosive engine, the combination with the engine cylinder, piston and crank shaft, of a valve casing having inlet and exhaust ports and communicating with the head end of the engine cylinder, a main slide valve in said casing arranged to alternately connect said cylinder to said inlet and exhaust ports, a supplemental slide valve for cutting off communication with said cylinder during the compression stroke of the piston, means driven from the engine crank shaft for positively reciprocating said main slide valve, said main valve having a lost-motion connection with said supplemental valve for intermittently reciprocating the same, and said supplemental valve having periods of rest at the opposite ends of its movement, substantially as described.

4. In a four-cycle, explosive engine, the combination with the engine cylinder, piston and crank shaft, of a valve casing having inlet and exhaust ports and a port communicating with the head end of the cylinder, a main slide valve in said casing arranged to alternately connect said cylinder port to said inlet and exhaust ports, a supplemental valve closing said cylinder port during the compression stroke of the piston, and means driven from the engine crank shaft for positively reciprocating said main slide valve, said latter valve having a lost-motion connection with said supplemental valve arranged to engage and shift the same at the ends of the movement of said main valve substantially as described.

40 5. In an explosive engine, the combination with an engine cylinder, piston and crank shaft, of a valve casing having a cylindrical bore and provided with inlet and exhaust ports and communicating with the engine cylinder, a reciprocating piston valve and a sleeve valve fitted within said casing for alternately connecting said cylinder to said inlet and exhaust ports, and means
45 driven from the engine shaft for reciprocating said piston valve, said sleeve valve being frictionally held in position and said piston valve having a lost-motion connection
50 with said sleeve valve to intermittently reciprocate the same and allow periods of rest to said sleeve valve at the opposite ends of
55 its movement substantially as described.

its movement, substantially as described.
6. In a four-cycle, explosive engine, the
combination with the engine cylinder, pis-
60 ton and crank shaft, of a valve casing hav-
ing a cylinder port and inlet and exhaust
ports and an intermediate port communi-
cating with the head end of the engine cyl-
inder, a piston valve fitting said casing and
65 movable across said cylinder port to alter-

nately connect the same to said inlet and exhaust ports, a pitman connected to said piston valve for reciprocating the same, two-to-one gearing driven from the engine shaft for operating said pitman, a sleeve valve 70 frictionally held in position in said casing and having a lost-motion connection with said piston valve and arranged to be intermittently reciprocated thereby, said sleeve valve being arranged to close said cylinder port during the compression stroke of the engine piston, substantially as described. 75

7. In an explosive engine, the combination with the engine cylinder, piston and crank shaft, of a valve casing having an open ended cylindrical bore with inlet and engine cylinder ports in its side walls, a reciprocating piston valve in said casing movable across said cylinder port, a piston cross-head in said casing connected to said piston valve, a pitman driven from the engine shaft and connected to said cross-head, and a sleeve valve in said casing between said piston valve and cross-head and arranged to be intermittently reciprocated thereby to open and close said cylinder port, said sleeve valve having periods of rest at the opposite ends of its movement, substantially as described. 80 85 90

8. In an explosive engine, the combination with the engine cylinder, piston and crank shaft, of a valve casing having a cylindrical bore and a port communicating with the engine cylinder; a sleeve valve for opening and closing said port fitted within the bore of said casing and frictionally held in position therein, a reciprocating member having a lost-motion connection with said sleeve valve to intermittently reciprocate the same and allow periods of rest thereto at the opposite ends of its movement and means for positively reciprocating said member driven from the engine shaft, substantially as described. 100 105

9. In a four-cycle, explosive engine, the combination with the engine cylinder, piston and crank shaft, of a valve casing having inlet and exhaust passages and communicating with the head end of the engine cylinder, a main slide valve in said casing arranged to alternately connect said cylinder to said inlet and exhaust passages, a supplemental slide valve for cutting off communication with said cylinder during the compression stroke of the piston, and means driven from the engine crank shaft for reciprocating said main slide valve, the latter having a lost-motion connection with said supplemental valve arranged to engage and shift the same at the opposite ends of the movement of said main valve, substantially as described. 110
115
120
125

10. In an explosive engine, the combination with the engine cylinder, piston and crank shaft, of a valve casing having inlet 130

and exhaust passages and communicating with the head end of the engine cylinder, main and supplemental slide valves in said casing coöperating to alternately connect said cylinder to said inlet and exhaust passages, said valve casing having a common seat for said valves, and means driven from the engine crank shaft for reciprocating said main slide valve, the latter having a lost-motion connection with said supplemental valve for shifting the same to the opposite ends of the movement of said main shaft and said supplemental valve having periods of rest at the opposite ends of its movement, substantially as described.

11. In an explosive engine, the combination with an engine cylinder, piston and crank shaft, of a valve casing having a cylindrical valve seat and communicating with the engine cylinder, a reciprocating piston valve and a sleeve valve fitted within the cylindrical valve seat of said casing and arranged to control the admission and exhaust of gases to and from said cylinder, and means driven from the engine crank shaft for reciprocating said piston valve, the latter having a lost-motion connection with said sleeve valve to intermittently shift the same at the opposite ends of the movement

of said piston valve, substantially as described.

12. In a four-cycle explosive engine, the combination with an engine cylinder, piston and crank shaft, of a valve casing having a cylindrical bore and provided with inlet and exhaust passages and communicating with the head end of the engine cylinder, a reciprocating piston valve fitting the cylindrical bore of said valve casing and arranged to alternately connect said cylinder to said inlet and exhaust passages, a sleeve valve fitting the cylindrical bore of said valve casing and arranged to cut off communication with said cylinder during the compression stroke of the engine piston, and means driven from the engine crank shaft for reciprocating said piston valve, the latter having a lost-motion connection with said sleeve valve to intermittently shift the same at the opposite ends of the movement of said piston valve, and said sleeve valve having periods of rest at the opposite ends of its movement, substantially as described.
